DIRECTIONAL TRANSMISSION LINE
TRANSDUCER

Lowell E. Norton, Princeton Junction, N. J., assignor to Radio Corporation of America, a corporation of Delaware

Application June 9, 1948, Serial No. 31,850

8 Claims. (Cl. 333—33)

1

This invention relates to directional transducers, and more particularly to directional transducers for use with transmission lines.

When speaking of transmission lines herein, the term is used generically to denote an electrical line for the conduction of electromagnetic energy, so that the term includes hollow pipe waveguides, as well as two-conductor transmission lines such as coaxial transmission lines or coaxial waveguides, and open wire transmission lines. In using transmission lines for the conduction of energy from a source or generator to a load, it is ordinarily desirable that the load presented to the generator shall be substantially free of changes due to changes in the load at the far end of the line. This is particularly true with magnetron generators for example. It is well known that magnetron generators are particularly sensitive to changes in load which cause the generator to change the frequency of the generated waves, or to increase or decrease the amplitude of the generated waves. Thus, the phenomenon of "pulling" in connection with magnetrons is well known to the art. This problem becomes particularly acute when the final or useful load, such as an antenna, to which the power from the generator is fed, is physically located some distance from the generator. The power is usually fed to the antenna along a transmission line which is many wavelengths long when high frequencies are employed. As a result slight changes in the antenna loading are magnified due to the long electrical length of the line. The magnified change in load presented to the generator may be minimized by placing in the line a directional transducer. A directional transducer is a device which is preferential to the passage of electromagnetic energy in one direction over passage in the reverse direction. When such a directional transducer is inserted in the transmission line between the generator and the load, and preferably placed near the load, the effect of slight changes in the load is considerably minimized because the impedance thereafter presented to the transmission line at its junction with the directional coupler now changes only slightly with load changes.

It is an object of the present invention to provide a novel directional transducer.

It is a further object of the invention to provide such a transducer which is of particularly simple structure.

It is a further object of the invention to provide a transmission line directional transducer of improved directional characteristics.

2

It is another object of the invention to provide a directional transducer relatively insensitive to load changes.

These and other objects, advantages, and novel features of the invention will be more clearly understood from the following description taken in connection with the accompanying drawing in which:

Figure 1 is a schematic diagram of an open wire transmission line between a high frequency generator and a load and employing the directional transducer of the invention;

Figure 2 is a face view of a directional transducer of the invention as used in a rectangular waveguide transmission line;

Figure 3 is a face view of a directional transducer of the invention using circular waveguide;

Figure 4 is a sectional view of a directional transducer of the invention in a rectangular waveguide in which the coupling between the shunt section and the waveguide proper is less than unity;

Figure 5 is a face view of a directional transducer employing a plurality of directional transducer sections of rectangular waveguide according to the invention;

Figure 6 is a sectional view of a directional transducer of the invention using a highly resistive impedance termination.

In accordance with the invention, my directional transducer comprises a section of transmission line, a reentrant transmission line portion, and an impedance termination, preferably energy absorbent, inserted in the reentrant portion. With the termination impedance of proper value and properly placed, the desired directional transducer and other desirable characteristics are secured, as will appear more fully hereinafter.

Referring now more particularly to Figure 1, there is shown a generator 10, which may be a magnetron or any other type of ultra-high frequency generator. The generator may be matched to the line 14 through the transducer by any of various well known means, not shown. The generator 10 is coupled to a load 12 through an open two-wire transmission line 14 and a directional transducer of the invention comprising the section 16 of transmission line 14, which may be considered a portion of the line 14, and a section of transmission line 18 reentrant with line 14 and in shunt with the portion 16. The load 12 may also be matched to the line by any of various well known means, not shown. The impedance Z_1 terminates the section 18 at a point

intermediate to two junctions with line 14. The section 16 has a length a . The distance from the junction 20 between the transmission line section 18 and the section 16 at the point of incident energy and the point at which impedance Z_1 terminates the line section 18 has a length c . The distance between the point at which impedance Z_1 is shunted across the line section 18 and the junction 22 of line section 18 on the load side of line 14 is b .

The directional transducer of Figure 1 may be analyzed by considering the impedance Z_T looking into the transducer arrangement at the junction 20, that is looking in the direction from the generator to the load. The following set of equations may be derived by inspection of the figure:

EQUATIONS 1 to 8

$$I_{ta} = I_{ra} \cos \beta a + i \frac{E_r}{Z_k} \sin \beta a \quad (1)$$

$$I_{tb} = I_{rb} \cos \beta b + i \frac{E_r}{Z_k} \sin \beta b \quad (2)$$

$$I_{tc} = I_{rc} \cos \beta c + i \frac{E_{rc}}{Z_k} \sin \beta c \quad (3)$$

$$I_{rc} = I_Z + I_{tb} \quad (4)$$

$$I_{ra} + I_{rb} = I_r \quad (5)$$

$$E_{ta} = E_T = E_r \cos \beta a + i I_{ra} Z_k \sin \beta a \quad (6)$$

$$E_{tb} = E_{rc} = E_r \cos \beta b + i I_{rb} Z_k \sin \beta b \quad (7)$$

$$E_{tc} = E_t = E_{rc} \cos \beta c + i I_{rc} Z_k \sin \beta c \quad (8)$$

In the foregoing equations, the I 's are current expressions, the E 's are voltage expressions and β is the propagation constant. Thus

$$\beta = \frac{2\pi}{\lambda}$$

where λ is the line wavelength. All of the lines have a characteristic impedance Z_k . The subscripts indicate the points at which the current and voltage values are taken, and are marked on Figure 1 in such a fashion as to be self-explanatory to those skilled in the art. From this set of equations it is possible to derive the following expression for Z_T .

$$Z_T = \frac{\frac{iZ_k}{2} \{ \cos [\beta(a+c)] - \cos [\beta(a+c)] \}}{\frac{1}{\sin [\beta(a+c)] - \frac{2}{Z_1} \frac{\sin [\beta(b+c)]}{iZ_k \cos \beta(b-c) - \cos [\beta(b+c)]} + \frac{iZ_k}{2 \sin \beta a} \{ \cos [\beta(b+c)] - \cos [\beta(b+c)] \}} + \frac{1}{\frac{iZ_k \sin [\beta(a+b)] - Z_k^2 \sin \beta b}{\sin \beta a} - \frac{Z_k^2 \sin \beta b}{Z_k} - \frac{\sin \beta b}{\frac{1}{Z_1} + \frac{2}{iZ_k \cos [\beta(b-c)] - \cos [\beta(b+c)]} \frac{\sin [\beta(b+c)]}{\sin \beta b}} + \frac{1}{\frac{1}{Z_k} + \frac{1}{iZ_k \sin \beta a \sin \beta b} \frac{\sin [\beta(a+b)]}{\sin \beta c}} + \frac{iZ_k \sin \beta b \sin \beta a}{\sin \beta c}} + \frac{1}{\frac{Z_k^2 \sin \beta b}{Z_1} + \frac{\sin \beta b}{\frac{1}{Z_k} + \frac{1}{iZ_k \sin \beta a \sin \beta b} \frac{\sin [\beta(a+b)]}{\sin \beta c}} - \frac{iZ_k \sin [\beta(b+c)]}{\sin \beta c}} \quad (9)$$

The various characteristics of the directional transducer section may be analyzed by means of Equation 9. Such analysis shows that this transducer section in general has directional transmissive characteristics. In other words, it preferentially transmits energy in one direction rather than in the reverse direction. The result of such directional characteristics may also be expressed by saying that the directional coupler 75

section, looking into the section in the direction in which the passage of incident energy is favored, appears to be a substantially stable load. This may be stated still another way qualitatively by saying that whatever impedance may appear on the remote side of the line, that side of the line nearer the generator sees a load which tends to receive energy but from which energy is reflected, if at all, in relatively constant amounts. 10 This results because the transducer tends to prevent the return of energy reflected from whatever load may be placed on the remote side of the directional transducer.

The action of the transducer shown in Figure 1 is not truly susceptible of qualitative analysis. The only proper approach to ascertain the action thereof is by inspection and study of Equation 9. The new transducer presents to the line a substantially constant impedance within moderate limits of variation of the various parameters. This is equivalent to saying that the relative variations in input impedance, Z_T , are less than the relative changes in terminal impedance, Z_R , and therefore the mis-matches and reflections due to the undesired changes in Z_R have less effect upon the generator than they would have produced without the network. Nevertheless, before showing that such a result occurs, at least for certain selected values of the parameters involved in the equation, we may qualitatively review the structure of Figure 1 with a view to a better understanding of its operation.

The generator looks into a line at the end of which the line looks into an impedance. This impedance is the impedance Z_T of the equations above. At the junction 20 at which this impedance is calculated, it will be observed that the incident energy splits in two directions, neglecting for the moment any portion which may be reflected. One portion travels the line section 16 to the junction 22 and the other portion travels the line section 18, and only a part of this second portion reaches the junction 22 because of the interposition of the line termination Z_1 . A moment's consideration will convince one that it is possible to choose the line lengths and impedance Z_1 in such a way that reflections

from the useful load are substantially or even entirely cancelled at the junction 20 with reflections from impedance Z_1 , whereas energy from junction 20 is transmitted at junction 22 toward the load. One of the important characteristics of the new transducer arrangement, however, cannot be explained in such a simple manner. This characteristic is the insensitivity of Z_T to changes in the impedance Z_R .

Returning now to the analysis of Equation 9, an example will be given of certain specific values which may be chosen to give particularly desirable results. Assume that βa is $\pi/2$, that βb is a , and that βc is $a+\pi/2$. With this set of values, Equation 9 reduces to the following equation:

$$Z_T = \frac{iZ_K \cos \alpha}{\left\{ -\sin \alpha + \frac{2iZ_K Z_1 \cos^2 \alpha - Z_K^2 \sin \alpha \cos \alpha}{Z_K^2 Z_1 (1 - 2 \sin^2 \alpha)} + \frac{iZ_K^3 \sin \alpha}{Z_R \cos \alpha} + \frac{2iZ_1 Z_K \sin \alpha}{Z_R} \right.} + \left. \frac{2iZ_R Z_K - Z_K^2 \tan \alpha}{Z_K^2 (2 - 3 \sin^2 \alpha)} + \frac{2iZ_K Z_R \sin \alpha + iZ_K^3 \sin \alpha}{Z_R \cos \alpha} \right\}} \quad (10)$$

It is clear, because of the periodicity of the functions involved that βa , βb , and βc may each be changed by amounts of 2π without altering these results. Even with the assumptions already made, there are still many possible values to choose which make Z_T relatively constant with changes in Z_R . If Z_T remains constant in this sense, at a value of Z_R , then the standing wave ratio between a generator and Z_T is substantially independent of changes in Z_R . Choose, for example, a as $(2N-1)\pi$, where N is an integer. Then βa is $\pi/2$, βb is $(2N-1)\pi$, and βc is $(2N-1)+\pi/2$. Equation 10 then reduces to:

$$Z_T = \frac{Z_K^2 (Z_R + Z_1)}{Z_R^2 + 3Z_1 Z_R} \quad (10A)$$

Again, it will be understood that any of the quantities βa , βb , βc may be different by 2π from the above assumed values, without altering the results.

The termination Z_R may be considered as the impedance of the useful load. It will be understood that Z_R is subject to various changes, for example, changes due to ambient temperature variations. Now, it is desired that at least for small changes in Z_R the impedance Z_T shall remain small. The present structure has a further advantage. Not only is the per unit change in Z_T with respect to per unit changes in Z_R small, or even zero at selected values, but the second rate of change, of Z_T with respect to Z_R is also small. This characteristic is even more important than it is that the first rate of change be small. The importance of this advantage is that over a substantial range of values of Z_R the rate of per unit change of Z_T with respect to per unit changes in Z_R is small. In other words, the slope of the curve of Z_T plotted with Z_R as an independent variable is small and remains small over a wide range of values. This range of values may readily be found to the desired degree of accuracy and for the desired limiting values of the slope, by making the plot of Z_T against Z_R to scale. To calculate it is very difficult. When we say the slope is small, we mean that it is fractional, that is, less than one.

Let

$$Z_{K1} = \frac{Z_K}{\sqrt{2}}$$

be the characteristic impedance of a section of a quarter wavelength transmission line at one end of which there is a termination having an impedance substantially equal to the load impedance Z_R and undergoing substantially the same changes, for example, those due to ambient tem-

perature variations. The other end of this quarter wavelength line section is connected in Figure 1 to form the termination impedance Z_1 , so that

$$Z_1 = \frac{Z_{K1}^2}{Z_R} = \frac{Z_K^2}{2Z_R}$$

If Z_R may change to $(1+\Delta)Z_R$ where Δ is con-

siderably less than one, say less than $\frac{1}{10}$, it may be shown that

$$Z_T = \frac{Z_K}{5 + 7/3\Delta}$$

approximately, which indicates that the change in Z_T is only about 45% as great as that in Z_R . As a second example if Z_1 is made of a material like barium titanate which has a decreasing resistivity with field strength, then by suitable choice of Z_K , Z_{K1} , and Z_1 it is again possible to reduce the variation of Z_T with changing Z_R .

For $Z_1 = Z_R$, and assuming that Z_R changes to $Z_R(1+\Delta)$ where Δ is considerably less than one, then it may be shown that

$$Z_T = \frac{Z_K^2}{2 + 3/4\Delta}$$

which indicates a change in Z_T only about 37% as great as the change in Z_R . Thus it will be observed that with such disparate values as $Z_1 = Z_K^2/2Z_R$ and $Z_1 = Z_R$, for the two conditions, the difference in the rate of change of Z_T with Z_R varies only by about 8%.

Referring now to Figure 2, which is a sectional view of a directional transducer of the invention, a quarter wavelength section 30 of hollow pipe rectangular cross-section transmission line is shunted by a section 32 of similar hollow pipe line. The section 32 of transmission line is re-entrant on the section 30 having junctions therewith at 34 and 36. A line termination 38 is inserted in the section 32 at a distance an odd number of half wavelengths from the junction 36 and the same odd number of half wavelengths plus a quarter wavelength distant from the junction 34. Thus the length of the entire section 32 is twice an odd number of half wavelengths plus a quarter wavelength, as may be the case for the specific values chosen for Figure 1 to derive Equation 10. Since βa , βb , and βc occur in periodic functions with a periodicity of 2π , any of these lengths may be varied a full wavelength without affecting the result. Of course, values must be chosen which result in physically realizable line sections. The directional transducer illustrated in Figure 2 may be inserted in a waveguide transmission line by utilizing the coupling members 40 and 42 which may be conventional. As shown in Figure 2, the coupling member 40 will be inserted on the generator side of the line, or that side of the line transmission which is to be favored. A similar directional transducer is shown in Figure 3 in face view, in which the waveguide transmission line is cylindrical in cross-section and the construction and nature

70
75

thereof will be obvious to those skilled in the art from what has been said heretofore.

It will be observed that in Figures 2 and 3 the coupling of the reentrant section is effected by utilizing a complete opening formed at the intersection of the internal surfaces of the line section and the reentrant section at the junctions. A somewhat different arrangement is shown in Figure 4 illustrating a directional transducer of the invention for use with rectangular waveguides. In Figure 4 the junctions are at 50 and 52. The section of the main line is 54 and the reentrant section is 56. The termination in line 56 is shown at 58 as a waveguide stub, similar to the stubs utilized for such terminations in Figures 2 and 3. However, at all of the junctions shown in Figure 4, the coupling between, for example, the reentrant section 56 and the line section 54 at 50 and 52, are formed by windows in section 54 allowing only limited communication at the junction between section 54 and the reentrant section 56. I often prefer the use of such window couplings, because they reduce the coefficient of coupling between the line proper and the reentrant section and thus tend to avoid reflections back in the direction from which the incident energy arrives. The directional transducers of Figures 2, 3 and 4 may be analyzed by the same methods employed in the analysis of the coupler of Figure 1, and with the similar results. The appropriate application of these formula to the waveguide structures will be understood by those skilled in the art from what has been said heretofore.

A preferred embodiment of the invention is that illustrated in Figure 5 which includes a plurality (three of which are shown) of such directional transducers as those shown in Figure 4 placed in tandem along the line. Directional effects are enhanced by using a plurality of the directional transducers of Figure 4 arranged as shown in Figure 5, each of which contributes to the directional transducer effect and yet, because of the small coefficient of coupling with the reentrant portions, reflections from the transducer of the incident energy back in the direction from which it arrives are reduced. With a plurality of such sections, any change in impedance looking into the first section due to the change in a load on the end of the other section will be reduced as the product of the fractional change, at least for very small changes to a first approximation, which would be resultant from one alone; thus supposing that for each of two such sections, the change in Z_T is about $\frac{1}{2}$ for a given change in Z_L in the notation of Figure 1. When combined the change in Z_T of the two sections will be about $\frac{1}{4}$ for the same change in the load. Lossy material may be included in the terminations 59, as shown.

Figure 6 shows a directional transducer of the invention which is inserted in a coaxial line. The termination impedance Z_T in this instance comprises a resonant cavity 60 coupled to the reentrant branch 62 by a line stub 64. The cavity is coupled to the line stub 64 by an exciting probe 66. The cavity is filled with an energy absorbent material 68 to increase the resistive component to a desired value. A high resistive component is generally desirable in the termination impedance Z_T . Coupling may be further reduced by removing a part of the contacting portions 62a and 62b to provide capacitive coupling of the shunt section.

What is claimed is:

1. A linear passive network directional transducer comprising a transmission line section substantially a quarter wavelength long at the operating frequency, a reentrant transmission line section having junctions with said quarter wavelength section at the ends thereof, an impedance termination in said reentrant section at a point an odd number of half wavelengths from one said junction and an odd number of half wavelengths plus a quarter wavelength distant from the other said junction, said impedance termination terminating the portions of said reentrant line section on each side thereof in a highly resistive power absorbing impedance having a value different substantially from that of the characteristic impedance thereof.

2. A linear passive network directional transducer comprising a first transmission line section having a length $\lambda/4 + (n_1 - 1)\lambda$ at the operating frequency, a reentrant transmission line section having junctions with said first section at the ends thereof, and a highly resistive power absorbing impedance termination in said reentrant section at a point $(2n_2 - 1)\lambda/2$ from one said junction and $(2n_3 - 1)\lambda/2 + \lambda/4$ from the other said junction, n_1 , n_2 and n_3 each being a positive whole number, λ being the line wavelength at the frequency of operation the impedance of said termination being substantially different from the characteristic impedance of said reentrant section.

3. A linear passive network directional transducer comprising a first transmission line section having a length $\lambda/4 + (n_1 - 1)\lambda$ at the operating frequency, a reentrant transmission line section having junctions with said first section at the ends thereof, and an impedance termination in said reentrant section at a point $(2n - 1)\lambda/2$ from one said junction and

$(2n_3 - 1)\lambda/2 + \lambda/4$

from the other said junction, n_1 , n_2 and n_3 each being a positive whole number, λ being the line wavelength at the frequency of operation, said termination impedance including a highly resistive power absorbing component and differing substantially in value from the line characteristic impedance.

4. The directional transducer claimed in claim 2, wherein said transmission line sections are hollow pipe wave guides.

5. The directional transducer claimed in claim 2 wherein said transmission line sections are two-conductor transmission line sections.

6. The directional transducer claimed in claim 1, the coupling between the sections at said junctions being very much less than unity coupling.

7. The combination comprising a plurality of transducers as claimed in claim 1, connected in tandem.

8. The combination comprising a plurality of transducers as claimed in claim 2, connected in tandem.
